US00D630952S

(12) **United States Design Patent**
Nies et al.

(10) **Patent No.:** **US D630,952 S**
(45) **Date of Patent:** **** Jan. 18, 2011**

(54) **CONTROLLER UNIT**

(75) Inventors: **Juergen Nies**, Winchester, VA (US); **Ha Van Duong**, Winchester, VA (US); **Vicky Ann Michael**, Winchester, VA (US); **Richard King Boyle**, Winchester, VA (US); **James Daniel Carter**, Winchester, VA (US)

(73) Assignee: **Melnor, Inc.**, Winchester, VA (US)

(**) Term: **14 Years**

(21) Appl. No.: **29/365,278**

(22) Filed: **Jul. 7, 2010**

(51) **LOC (9) Cl.** **10-03**

(52) **U.S. Cl.** **D10/40**

(58) **Field of Classification Search** D10/40; 368/107-123, 82-84, 187; 700/284; 137/624.11-624.19, 137/624.2, 624.21; 239/69, 70

See application file for complete search history.

(57) **CLAIM**

The ornamental design for a controller unit, as shown and described.

DESCRIPTION

FIG. 1 is a perspective view of a controller unit;

FIG. 2 is a front view of the controller unit;

FIG. 3 is a rear view of the controller unit;

FIG. 4 is a top view of the controller unit;

FIG. 5 is a bottom view of the controller unit;

FIG. 6 is a left side view of the controller unit; and,

FIG. 7 is right side view of the controller unit.

The broken lines are used to show portions of the controller unit that do not form part of the claimed design.

1 Claim, 6 Drawing Sheets
